TROUGHED CONVEYOR BELT

Maurice J. De Wulf, Lake Bluff, Ill., assignor to United States Steel Corporation, a corporation of New Jersey
Filed Feb. 27, 1962, Ser. No. 176,008
3 Claims. (Cl. 198—201)

This invention relates to a troughed conveyor belt and more particularly to a belt formed of coiled wires interconnected by cross wires. One such belt is shown in Blackburn Patent No. 2,278,859 dated April 7, 1942. In this belt the ends of the cross wires are secured to the ends of the coiled wires at the top of the side flanges by an electric weld. Dirt or the product being conveyed can be caught or lodged in the spiral wires at the top of the flanges. Also, since the top of the flange is rough there is danger of a workman being injured by contact therewith.

It is therefore an object of my invention to provide a troughed conveyor belt having means for preventing material from being caught or lodged in the top of its side flanges.

This and other objects will be more apparent after referring to the following specification and attached drawings, in which:

FIGURE 1 is a top plan view of a section of a conveyor belt incorporating my invention therein;

FIGURE 2 is a perspective view of the belt of FIGURE 1;

FIGURE 3 is a side view of the belt of FIGURE 1 showing it passing around a pulley;

FIGURE 4 is a side view of one flange of the belt showing a second embodiment of my invention; and

FIGURE 5 is a view, similar to FIGURE 4, showing a third embodiment of my invention.

Referring more particularly to FIGURES 1, 2 and 3 of the drawings, reference numeral 2 indicates a portion of an endless troughed conveyor belt. The conveyor belt has a flat portion 4 and upwardly turned side flanges 6 and 8, one at each longitudinal edge of the belt. The belt is formed of a plurality of coiled wires 10 and 12 interconnected by cross wires 14. The wires 10 preferably are coiled in the opposite direction from wires 12. The cross wires 14 are bent upwardly as best shown in FIGURE 3. Part of the cross wires may terminate short of the top edge of the belt as shown with the others extending above the coiled wires 10 and 12.

According to my invention U-shaped clips 16 are welded to the top or outer end of at least some of the cross wires 14 with the legs of the clip arranged on opposite sides of the flange and extending downwardly toward the flat portion 4. It will be seen that the clips 16 are arranged in substantially abutting relationship. In FIGURE 3 the belt is shown passing around a pulley 18. It will be apparent that the clips 16 forming the selvage edge of the belt prevent the product being conveyed from becoming caught or lodged in the belt while at the same time they permit articulation of the belt around the pulleys of the conveyor. This construction also eliminates the need of attaching the spiral wires to the cross wires as in the Blackburn patent.

The belt of FIGURE 4 has the same construction as that of FIGURE 1 and the same reference numerals are used to indicate corresponding parts. In this embodiment

2

U-shaped clips 20 are welded to the end of the cross wires 10 with alternate clips 20 overlapping the ends of the clip therebetween.

The belt of FIGURE 5 also has the same construction as that of FIGURE 1 so that like parts are indicated by the same reference numerals. In this embodiment U-shaped clips 22 are fastened to the ends of cross wires 10, but with one end of each clip overlapping the adjacent end of one adjacent clip and the other end being beneath the adjacent end of the other adjacent clip.

The arrangements shown in FIGURES 4 and 5 are preferably used where there is danger of the conveyed product being caught between the ends of the clip.

While several embodiments of my invention have been shown and described it will be apparent that other adaptations and modifications may be made without departing from the scope of the following claims.

I claim:

1. A conveyor belt comprising a flat portion and a flange at each longitudinal edge of said flat portion, said belt being formed of coiled wires interconnected by cross wires, at least some of said cross wires being U-shaped with the legs of the U extending to the outer end of each flange, and a plurality of relatively short U-shaped clips attached to the outer end of each flange with the legs of the clips arranged on opposite sides of the associated flange and extending toward said flat portion, the clips on each flange being arranged in substantial abutting relationship along the length of the flange.

2. A conveyor belt comprising a flat portion and a flange at each longitudinal edge of said flat portion, said belt being formed of coiled wires interconnected by cross wires, at least some of said cross wires being U-shaped with the legs of the U extending to the outer end of each flange, and a plurality of relatively short U-shaped clips attached to the outer end of each flange with the legs of the clips arranged on opposite sides of the associated flange and extending toward said flat portion, the clips on each flange being arranged with their ends in overlapping relationship along the length of the flange.

3. A conveyor belt comprising a flat portion and a flange at each longitudinal edge of said flat portion, said belt being formed of coiled wires interconnected by cross wires, at least some of said cross wires being U-shaped with the legs of the U extending to the outer end of each flange, and a plurality of relatively short U-shaped clips attached to the outer end of each flange with the legs of the clips arranged on opposite sides of the associated flange and extending toward said flat portion, the clips on each flange being arranged along the length of the flange with one end of each clip overlapping the adjacent end of an adjacent clip and the other end being beneath the adjacent end of the other adjacent clip.
